UNITED STATES PATENT OFFICE.

ANTONIO ALBERICO, OF JOLIET, ILLINOIS

AEROPLANE.

1,346,107.

Specification of Letters Patent. Patented July 13, 1920.

Application filed May 21, 1919. Serial No. 298,688.

To all whom it may concern:

Be it known that I, ANTONIO ALBERICO, a citizen of the United States, residing at 608 North Chicago street, Joliet, county of 5 Will and State of Illinois, have invented certain new and useful Improvements in Aeroplanes, of which the following is a specification.

This invention relates to aeroplanes and 10 it has for an object to provide a novel type of aeroplane of great power suitable for carrying passengers and mail, and having its propelling means so arranged and constructed as to minimize risk of failure there- 15 of during flight.

For further comprehension of the invention, and of the objects and advantages thereof, reference will be had to the following description and accompanying drawings, and to the appended claims in which the various novel features of the invention 20 are more particularly set forth.

Figure 1 of the drawings is a side elevation of an aeroplane embodying the invention; 25

Fig. 2 is a front elevation thereof;

Fig. 3 is a plan view thereof;

Fig. 4 is an enlarged fragmentary longitudinal sectional view showing the forward 30 part of the aeroplane body and the disposition of the power plant therein;

Fig. 5 is a front view, partly in section, of the lifting and trailer propeller equipped with running gear;

Fig. 6 is a fragmentary sectional view on the line 6—6 of Fig. 5;

Fig. 7 is a detail view of a portion of the drive connections to the side tractor propellers; and

Fig. 8 is a diagrammatic view of the drive connections to the rear propeller.

As here shown my improved aeroplane comprises an elongated body divided into an upper story or section 1, and a lower 45 story or section 2. I have here shown the aeroplane as of the biplane type having a pair of lifting planes 3 and 4, secured in any suitable way to the body of the aeroplane and braced by the vertical struts 5, and diagonal braces 6.

It will be understood that the number of lifting planes may be varied, a biplane structure for instance being also suitable.

The planes may be provided with the usual balancing ailerons as indicated at 7, while 55 the rear end of the body may be provided with a rudder 8, and stabilizing plane 9, of the usual type. The detail construction of the planes and the rudder and stabilizing means need not be set forth here, since they 60 will be made up in the manner common to aeroplanes.

According to my invention I provide a novel arrangement of propelling means comprising a pair of propellers 10 and 11, located centrally of the sections 1 and 2 of the body respectively, and a pair of side propellers 12 and 13, located in opposite sides of the body and just in front of the planes. These propellers may be all of ordinary construction and are designed to exert a tractive force only.

I also provide another series of propellers which are of a novel construction, and which comprise a central propeller 14 located 75 under the rear end of the body, and a pair of side propellers 15 located under the lifting plane 4. These propellers are mounted on shafts, 16 and 17, respectively, which extend transversely beneath the 80 body, the propellers each consisting of a plurality of capped vanes 18 which radiate from the hubs 19 by which the propellers are fixed to the shafts.

The shaft 16 is a steel shaft, and is journaled in suitable bearings in a semi-cylindrical housing 20, which is mounted on the underside of the aeroplane body. The shaft 17 extends transversely between the propellers 15, being journaled at its ends in housing 90 21, similar to the housing 20, secured under the plane 4. Intermediate its ends the shaft 17 may be supported in the bearing 22 depending from the body of the aeroplane.

In order to render unnecessary the provision of additional landing and running gear I mount a novel form of landing and running gear on each of the propellers 14 and 15. As here shown a series of bowsprings 25' are secured at one end to rings 100 26', surrounding and fixed to the propeller vanes 18, and at their opposite ends to the wheel-rims 27 upon which are mounted tires 30 of any suitable construction.

The power plant of my improved aeroplane comprises a pair of motors for the

propellers 10 and 11, a second pair for the propellers 12 and 13, a third pair for the propellers 15, and a fourth pair for the propellers 14. For convenience in grouping, 5 one motor of each pair is located in the upper section of the aeroplane body, and the other in the lower section.

The motors of each pair drive through a common mechanism, each motor being of 10 sufficient power to drive the two propellers to which it is connected in case of breakdown of the other motor, motors of the latest internal combustion type of high power being preferably employed.

15 The motors for the propellers 10 and 11, are indicated at 35 and 36, (Fig. 4); for the propellers 12 and 13, at 37 and 38; for the propellers 15, at 39 and 40; and for the propeller 14 at 41 and 42, (see Fig. 1). The 20 first three pairs are preferably located in the forward end of the aeroplane body, and the last pair toward the rear end.

The propellers 10 and 11 are mounted on the forward ends of suitable journaled 25 shafts 44 and 45, having bevel gears 46 and 67 on their rear ends, which mesh with the bevel gears 48 and 49 on a vertical shaft 50, which extends from the lower section into the upper. Fixed to the shaft 50 in the 30 upper section is a bevel gear 51, which meshes with another bevel gear 52 on a shaft 53, connected by a clutch to motor 35. Similarly, a second bevel gear 54 is fixed to shaft 50 in the lower section, and 35 meshes with a bevel gear 55 on a shaft 56, connected by a clutch 57 with motor 36.

Immediately behind the motors 35 and 36 are located the motors 39 and 40 for the propellers 15. These motors drive the bevel 40 gears 60 and 61 meshing with bevel gears 64 and 65 on a vertical shaft 66, which extends below the body of the aeroplane, and has fixed on its lower end a bevel gear 67, meshing with a bevel gear 68 on the shaft 45 17 of the propeller 15.

Immediately behind the motors 39 and 40 are located the motors 37 and 38, which drive the propellers 12 and 13. These motors drive the bevel gears 70 and 71 through 50 the clutch connections 72 and 73. The gears 70 and 71 mesh with other gears 74 and 75, on a vertical shaft 76, upon which is fixed a third bevel gear 77 meshing in turn with a pair of bevel gears 78 and 79, fixed on the 55 inner ends of transverse shafts 80 and 81. On the outer ends of the shafts are fixed bevel gears 82 and 83, meshing with other gears 84 and 85, on the rear ends of longitudinally extending shafts 86 and 87, to the 60 forward ends of which are fixed the propellers 12 and 13.

A platform 88, tapering in width toward the rear is provided on a level with the floor of the upper story, this platform preferably 65 extending substantially the length of the

body, and being rigidly held by any suitable system of bracing. The shafts 80, 81 and 86, 87 may be journaled in suitable bearings, as indicated at 89, on the underside of the platform.

The connections from the motors 41 and 42 comprise a vertical shaft 90 driven from the motors by clutch connected bevel gears, as previously set forth, and driving a stub shaft 91, through the bevel gears 92 and 92' 75 on the end of which shaft is a sprocket wheel 93, connected by a chain 94 to a second sprocket wheel 93' on the shaft 16.

The body of the aeroplane may be fitted up in any suitable manner, as after the 80 fashion of railway cars, for the accommodation of passengers, and for the transportation of mail and express matter. A small cabin 95 may be provided in the forward end of the upper story for the pilot, in 85 which the usual control members, not necessary here to be shown, will be located. A ladder 96 may extend down one side of the aeroplane body through suitable openings in the floors of the cabin and upper story, for 90 use of the crew in passing from one compartment to another.

Having thus described my invention what I claim as new and desire to secure by Letters Patent, is:—

1. An aeroplane having a body divided into upper and lower stories, a propeller located centrally in front of each story, and a pair of side propellers located substantially midway of the height of the said body, 100 separate pairs of motors having the different motors of each pair located respectively in the upper and lower stories, and common driving connections between the said different motors of each pair and the center and 105 side propellers respectively.

2. An aeroplane having a pair of centrally located tractor propellers, a pair of side tractor propellers, and a combined lifting and tractor propeller located under rear end 110 thereof.

3. An aeroplane having a pair of central tractor propellers, a pair of side tractor propellers, and a plurality of combined lifting and tractor propellers disposed one under 115 the rear end of the body of the aeroplane and one on each side of the body under the lifting plane thereof.

4. An aeroplane having a body divided into upper and lower stories, a propeller located in front of each story, a motor located in each story, and a common driving connection between said motors and said propellers.

5. An aeroplane having a body divided 125 into upper and lower stories, a propeller located in front of each story, a motor located in each story, and a common driving connection between said motors and said propellers, said aeroplane including a verti- 130

cal shaft extending from one story to the other and adapted to be clutch connected to either or both of said motors.

6. In an aeroplane, a combined land and air propeller disposed in the understructure and a load carrying housing covering the upper half of said propeller, the said understructure resting upon the said housing and the said propeller being journaled in the 10 said housing.

7. An aeroplane having an air propeller disposed in the understructure thereof on a transverse axis, a wheel member of less

width than said propeller surrounding said propeller, and bow springs extending from 15 the sides of the air propeller to the said wheel member to form a resilient mounting for the latter.

8. An aeroplane having an air propeller disposed in the understructure thereof on a 20 transverse axis, and a wheel member resiliently mounted on the peripheral edge of said propeller.

In testimony whereof I have affixed my signature.

ANTONIO ALBERICO.
